DUAL SOUND REPRODUCING DEVICE

Edward A. Rockwell, Chicago, Ill., assignor to
Patent Engineering Corporation, a corporation
of Delaware

Application December 26, 1931, Serial No. 583,251

12 Claims. (Cl. 250—14)

This invention relates to improvements in dual sound reproducing devices, such as are employed in loud speakers as used with talking motion pictures, radio receiving sets, etc. and has for its 5 principal object the production of a simple, efficient and economic sound reproducing device employing two units, one of the usual electromagnetic or dynamic type and the other of the piezo electric type.

10 Another object of the invention is to provide a device of this character embodying two units as aforesaid adapted for use in relatively small cabinets, the construction and arrangement of the units being such that diaphragm areas are obtained sufficiently large to faithfully reproduce sound waves in sufficient volume.

15 A further object of the invention is to provide a device of this character wherein the faithful reproduction of speech, music or other sounds is secured with maximum volume and clarity and with minimum distortion by reason of the fact that the capacity of the piezo electric unit is used to balance the impedance of the electromagnetic unit.

20 The invention consists substantially in the construction, combination, location and relative arrangement of parts as will be more fully herein-after set forth as shown by the accompanying drawings and finally pointed out in the appended

25 claims.

In many modern radio receiving sets or small outfits for talking motion pictures in the home, the sound reproducing device hereinafter termed a loud speaker is assembled with and mounted 30 in the cabinet of the set. Heretofore the magnetic speaker has been used almost exclusively in commercial sets and in order to secure satisfactory and adequate sound reproduction it has been necessary to employ a diaphragm of from 35 6 to 12" in diameter. The diameter of the diaphragm of the average cone speaker of the dynamic type is seldom less than 8" and when the diameter becomes 5" or less the reproduction and volume becomes unsatisfactory.

40 45 Radio receiving sets in which an electrically driven clock usually employing a synchronous motor are now coming into use. It is desirable that these sets shall not be larger than the ordinary mantel clock and should not be over 10" high, 7" wide and 6" deep. Obviously, the loud speaker in such a set cannot be of sufficient diameter to secure satisfactory tone reproduction in sufficient volume. The present invention however permits of placing two speaker units in a 50 55 cabinet of the size mentioned and the area of the

two diaphragms in the speaker units will be sufficient to produce in ample volume and faithful reproduction.

The invention will now be described employing a cabinet of approximately the dimensions herein given, utilizing as one of the speakers any suitable type of electromagnetic or dynamic device, many of which are well known, together with a piezo electric speaker, the driving element of which consists of a Rochelle salt crystal as 10 more fully described in the paper entitled "The use of Rochelle salt crystals for electrical reproducers and microphones" by C. Baldwin Sawyer, beginning on page 2020 of the Proceedings of the Institute of Radio Engineers for November, 1931, 15 Vol. 19, No. 11.

In the accompanying drawings:

Figure 1 is a front view partly in section of the cabinet of a radio receiving set containing two speaker units;

Figure 2 is a side view, partly in section, of the set, Figure 1;

Figure 3 is a isometric view of the two speaker units showing the magnetic unit partially surrounded and enclosed by the diaphragm of the 25 crystal unit, and

Figure 4 is a diagram of the circuits of the two speaker units.

The cabinet or case 10 may be of any suitable construction and is provided with the usual opening 11 for the magnetic speaker and also openings on its sides, one of which is shown in the sectional half of Figure 1 at 12, these openings permitting the sound produced by the diaphragm 22 of the crystal speaker to find egress from the cabinet.

The magnetic speaker comprises the usual mounting frame 13 in which is supported the cone diaphragm 14 and on which is mounted the exciting coil 15. The usual voice coil 15' is attached to the diaphragm 14 in the usual manner. The 40 speaker shown in the drawings is of the usual dynamic type and the step-down transformer 16 is mounted on the frame of the speaker as shown in Figure 2.

It will be understood that this magnetic speaker 45 may be of any known type and is mounted in the cabinet in any suitable manner.

The cabinet is provided with a base plate 17, preferably of metal, on which is firmly secured at opposite ends by means of the clamps or lugs 50 18 the Rochelle salt crystal 19. The lugs 18 are insulated from the base 17, if the latter is of metal. The lugs 18 form clamps that secure the opposed sections of the crystal together and these clamps extend along the ends of the crystal and terminate 55

in the lugs 20, 21 which are secured to the diaphragm 22 which is the full width of the cabinet and which extends around and over the magnetic unit enclosing the same on the sides as shown 5 in Figure 2. In this construction the vibrations of the crystal impart vibrations tangentially to the plane of the diaphragm as more fully described in the patent to J. H. Van Wagener No. 1,827,919 dated October 20, 1931 or the crystal may be 10 mounted and operated as disclosed in the pending application, Serial No. 570,292 filed October 22, 1931.

In the space below the magnetic speaker and above the crystal 19 is positioned the chassis 23 containing the usual parts that are necessary to 15 complete the radio receiver. The usual vacuum tubes are shown at 24, 25. The volume control is the projecting knob 26 and the tuning condenser knob is shown at 27. The usual dial 28 is 20 mounted immediately behind the tuning knob and may be seen through the aperture 29 in the front of the cabinet.

The chassis complete may be pushed into the cabinet 10 from the rear thereof, suitable flexible 25 connections (not shown) being employed to connect the two speaker units in the circuit.

If desired, the two speaker units may be mounted upon and form part of the chassis so that all 30 interior parts of the set including both speakers can be removed and replaced in the cabinet 10 without disconnecting any wires, similar to the chassis shown and described in the application, Serial No. 570,292 aforesaid.

The two speaker units may be connected in any 35 suitable manner. It has been found desirable to connect them in parallel as shown in Figure 4, the conductors 30, 31 being connected to the output of the radio receiving set and conductors 32, 33 to a suitable source of current for energizing the 40 dynamic speaker magnet. It will be observed that the capacity of the crystal 19 balances the impedance of the magnetic speaker and transformer 16. (In the event an ordinary magnetic speaker, not of the dynamic type, is used, the 45 transformer 16 may be omitted and the speaker winding connected directly across conductors 30, 31.)

It is known that the impedance of the magnetic 50 speaker increases with the frequency of the current impressed thereon and that the impedance of the crystal speaker decreases under the same conditions. Therefore, by proper balancing of the crystal capacity against the impedance of the magnetic speaker, that part of the output circuit 55 containing the speakers can be given an average impedance value best adapted to the particular use to which the dual speaker is to be put.

It will be obvious from the foregoing specification and a study of the drawings that the combined area of the two speaker diaphragms 14 and 60 22 is much greater than could be obtained by any other arrangement in a cabinet of any given size and that several advantages are inherent in this arrangement. The fact that the sound is emitted from the cabinet both from the front and sides 65 is an advantage and it has been found that the quality of the reproduced music or speech is improved by reason of the diaphragm arrangement and by reason of the balancing of the impedance 70 of the magnetic speaker by the capacity of the crystal speaker.

It has been found that by making the dynamic 75 speaker responsive to lower tones and the crystal speaker responsive to higher tones that the combination results in the faithful reproduction of

speech and music over a much greater range with greater fidelity than can be obtained by using either type of speaker separately. It appears that the dynamic speakers favor the base notes whereas the crystal speakers favor the treble or higher notes, so that this dual speaker is inherently perfect over a wide range of frequencies.

Although the invention has been disclosed in connection with the specific details of the preferred embodiment thereof, it must be understood 10 that such details are not intended to be limitative of the invention except insofar as set forth in the accompanying claims.

What is claimed is:

1. The combination of a magnetic speaker unit 15 having a diaphragm and means for vibrating the diaphragm, a speaker unit having a diaphragm surrounding a portion of said magnetic speaker unit, means including a piezo electric crystal for vibrating said last diaphragm, and connections 20 between said speaker units for simultaneously operating the same.

2. In combination with a magnetic speaker unit 25 having a diaphragm and means for vibrating said diaphragm, a second speaker unit having a dia- 25 phragm partly embracing said first unit and including a piezo electric crystal means for operating said last diaphragm, a cabinet containing said speakers having separate apertures therein adjacent said diaphragms, and connections be- 30 tween said speaker units for simultaneously operating the same.

3. In combination, a magnetic speaker unit 35 having a diaphragm and means for vibrating the diaphragm, a speaker unit having a diaphragm 40 and piezo electric means for vibrating the dia- phragm, a cabinet in which said units are mounted, said cabinet having a front wall and side walls, said magnetic unit having its diaphragm positioned adjacent said front of the cabinet and 45 said crystal speaker having its diaphragm positioned adjacent said side wall thereof and embracing a portion of said magnetic unit, said cabinet having apertures in its walls adjacent said diaphragms, and connections between said speaker units for simultaneously operating the same.

4. In combination, a cabinet, loud speakers 50 therein each speaker having separate means for driving the same, one of said speakers having a diaphragm flexed to form a portion of a cylinder, and radio receiving means in said cabinet connected to said speakers for simultaneously operating the same, said flexed diaphragm partly surrounding the radio receiving means and the other 55 of said speakers.

5. In combination, a cabinet, a chassis containing 60 radio receiving means in said cabinet, a loud speaker and a driver therefor in said cabinet, a second speaker in said cabinet having a diaphragm extending along the side of said chassis and partly embracing both the chassis and said first speaker, means below said chassis for operating said last diaphragm, and connections between 65 said last speakers including said radio receiving means for simultaneously operating the same.

6. In combination, a cabinet, a loud speaker mounted therein, a chassis in said cabinet, a base plate in said cabinet, a second speaker comprising a diaphragm surrounding a portion of said chassis, 70 actuating means for said diaphragm carried on said base plate, and connections between said speakers for simultaneously operating the same.

7. In combination, a cabinet, a loud speaker unit 75 including a cone diaphragm and actuating means

therefor, said unit being secured to a wall of the cabinet, a second speaker unit having a flat diaphragm flexed to form a portion of a cylinder embracing said first speaker and actuating means therefor mounted subjacent said last diaphragm, and connections between said speakers for simultaneously actuating the same.

8. In combination, a loud speaker comprising a mounting frame, a diaphragm supported thereby, a voice coil secured to said diaphragm, an exciting coil secured to said frame, a second speaker having a diaphragm surrounding said exciting coil, said diaphragm extending over and around a portion of said frame and having its plane surface parallel with the axis thereof, a driver for said second speaker, and connections between said speakers for simultaneously operating the same.

9. In a radio receiving set, a cabinet, a loud speaker mounted therein with its diaphragm secured to the front thereof, a chassis in said cabinet, said chassis containing a volume control device and a tuning condenser, control knobs for said device and condenser, said knobs extending outwardly from the front of said cabinet, a second speaker within said cabinet having a diaphragm extending along the sides and across the top thereof, said speakers connected for operation to said chassis and adapted to be controlled by said knobs, and circuits including said speakers and connected to said volume control device and

tuning condenser whereby said speakers may be simultaneously operated.

10. In a radio receiving set, a cabinet, a loud speaker therein, a base plate in said cabinet, a second speaker in said cabinet comprising diaphragm actuating means secured to said plate, a diaphragm connected to said means and extending along the inner side walls of said cabinet and across the top of same, and connections between said speakers for simultaneously operating the same.

11. In a radio receiving set, a cabinet, a loud speaker therein, a diaphragm extending along the inner side walls of the cabinet and across the top of same, means independent of said loud speaker for vibrating said diaphragm, and connections between said loud speaker and said vibrating means for simultaneously operating the same.

12. In a radio receiving set, a cabinet, a diaphragm within the cabinet covering substantially all the interior side and top wall thereof, means for vibrating said diaphragm supported by said cabinet, a loud speaker unit supported by said cabinet and having a portion of its operating parts within the space defined by said diaphragm, and connections to said means and said last speaker unit for actuating the same simultaneously.

EDWARD A. ROCKWELL. 30
